UNITED STATES PATENT OFFICE.

OTTO J. KUHLKE, OF AKRON, OHIO, ASSIGNOR TO THE AMAZON TIRE & RUBBER COMPANY, OF AKRON, OHIO, A CORPORATION OF OHIO.

DESIGN FOR AN ELASTIC VEHICLE-TIRE.

49,901.

Specification for Design.

Patented Nov. 14, 1916.

Application filed July 10, 1916. Serial No. 108,476. Term of patent 14 years.

To all whom it may concern:

Be it known that I, OTTO J. KUHLKE, a citizen of the United States, residing at Akron, Summit county, and State of Ohio, have invented a new, original, and ornamental Design for Elastic Vehicle-Tires, of which the following is the specification, reference being had to the accompanying drawings, forming part thereof.

In the drawings Figure 1 is a plan view of a portion of an elastic tire embodying this invention, and Fig. 2 is a cross sectional view of the same.

I claim,

The ornamental design for an elastic vehicle tire, as shown.

OTTO J. KUHLKE.
